UNITED STATES PATENT OFFICE.

WILLIAM E. ELLIOTT, OF GRAND RAPIDS, MICHIGAN.

KEY-TRANSFER MECHANISM.

1,175,623.

Specification of Letters Patent. Patented Mar. 14, 1916.

Original application filed March 8, 1915, Serial No. 12,907. Divided and this application filed September 17, 1915. Serial No. 51,181.

To all whom it may concern:

Be it known that I, WILLIAM E. ELLIOTT, a citizen of the United States of America, residing at Grand Rapids, in the county of 5 Kent and State of Michigan, have invented certain new and useful Improvements in Key-Transfer Mechanism; and I do hereby declare the following to be a full, clear, and exact description of the invention, such as 10 will enable others skilled in the art to which it appertains to make and use the same.

This invention relates to a key transfer mechanism by means of which a key is transferred from outside a casing containing controlling mechanism for automatically locking 15 a machine against operation after the completion of a predetermined number of cycles of operations by the machine.

The present invention is a division from 20 my copending application, Ser. No. 12,907, filed March 8, 1915. In said application the mechanism for controlling the operation of the machine is fully disclosed and in this application only such parts thereof as are 25 necessary for the understanding of the present invention relative to the key transfer mechanism is shown.

It is the main object and purpose of my 30 invention to provide a key transfer mechanism with new and useful features of construction and operation which will insure against the use of any but specially constructed keys, guarding against the use of fraudulent or counterfeit keys.

Subsidiary to this primary object the invention has for its objects the production of 35 various novel features of construction serving to permit the entrance of the key into the casing and transfer by novel mechanism to an operating plug which is designed to 40 carry the key into operative association with the controlling mechanism to thereby unlock it to permit another series of cycles of operations.

To these ends I have constructed the embodiment of my invention disclosed in the accompanying drawings, in which:

Figure 1 is a front elevation of the casing 45 inclosing the controlling mechanism and transfer device. Fig. 2 is a similar elevation with the outer removable plate of the casing with the transfer device removed. Fig. 3 shows in front elevation and in section an enlarged detail of the key. Fig. 4 50 shows, similarly, the transfer disk. Fig. 5

shows also in front elevation and in transverse section a detail of an intermediate member normally between the inner and outer plates of the casing. Fig. 6 is an enlarged sectional detail view taken through a key 60 and adjacent parts in the operation of transferring the key from the receiving opening in the casing to the operating plug. Fig. 7 is a horizontal sectional view taken through the casing and illustrating the key in the 65 plug in the operation of unlocking the mechanism. Fig. 8 is a similar view illustrating the transfer of the key from the transfer disk to the plug; and Fig. 9 is an elevation of the plug.

Like reference characters refer to like parts throughout the several views of the drawings.

The casing for containing the mechanism indicated at 1 has an open front side covered by a plate 2 on which the controlling mechanism forming the subject matter of my previous application is mounted. A sealing plate 3 is placed over the cover plate 2 and has a plurality of bosses 4 formed thereon through which screws or other suitable connecting devices pass to attach the plate in position, these bosses being adapted to receive seals 5 for sealing the plate against unauthorized removal. A reciprocating rod 6 passes through the casing and is operatively associated with the machine which is to be controlled by the controlling mechanism. A dog 7 is located adjacent the rod and is normally actuated away from the rod 75 occupying the position shown in Fig. 7. An irregularly shaped member 8 pivotally mounted in the casing and having spaced apart arms 9 and 10 controls the position of the dog 7 and when free to do so the arm 9 bears against the dog 7 forcing it against the reciprocating rod 6 and into a notch thereof, thereby stopping the machine with which the rod 6 is associated, from operation. This much of the mechanism is disclosed in the present application merely to show its connection with the structure which forms the subject matter of the present invention and it is fully described in detail in the application previously noted, from 80 which this invention is a division.

A plug 11 having an inner end 11^a substantially rectangular in cross section, and an outer end 11^b circular in cross section, is mounted in 105 the casing and extends through openings in 110

the inner and outer plates 2 and 3. At its inner end the plug is provided with a longitudinal slot 12 in which the arms of the member 8 may move back and forth and 5 with a transverse slot 13 adapted to receive the key 14. When the key is transferred to this slot and the plug forced inwardly the edge of the key bears against the inclined end 10^a of the arm 10 operating the 10 irregularly shaped member 8 to the right as shown in Fig. 7 and releasing the dog 7, thereby unlocking the reciprocating rod 6 for further operation.

The cover plate 2, adjacent the plug 11, is 15 formed with an inward projection 15 making a circular depression 16 in the front side of the plate. Through the cover in this depression, an opening 17 is cut sufficient to permit the insertion or withdrawal of the 20 plug, this opening at one side being substantially rectangular in outline so that the shoulders 18 of the plug may pass therethrough. Shoulders 18 are formed at the 25 junction of the circular and rectangular portions of the plug as shown. A plurality of ribs, three in number, are formed on the cover 2 in the depression 16 and are concentric with the center of the depression. A stud 20 cast integral with the inner plate 2 30 projects from the center of the depression around which is positioned a transfer plate 21 on its underside having curved grooves 22 adapted to receive the ribs 19 heretofore described. The disk is also formed with a 35 recess 23 in one edge of a size to receive the plug 11 and, at a diametrically opposed point, has an outwardly projecting pin 24 by means of which it may be manually operated about the stud 20.

40 Between the inner and outer plates 2 and 3 a member 25 substantially circular in outline is positioned being received in the depression 16 above disk 21. It is rigidly connected to the cover 2 by screws passing 45 through the projections 25^a and by a screw 26 which passes centrally through the member 25 and into the stud 20. On its underside this member 25 is provided with projecting ribs 27 circular in outline which seat 50 in grooves 28 formed on the outer surface of the transfer disk 21, it being understood that the grooves and ribs are also concentric with the ribs 19 and grooves 22 heretofore described. Through the member 25 a circular opening 29 is cut, the outer end of the 55 plug 11 extending through this opening, the withdrawal of the plug however, being prevented by reason of the stop interposed against the shoulders 18 thereof. An opening 30 is also cut through the disk 29 adapted to pass the key 14 and a curved slot 32 is provided in member 25 through which the pin 24 heretofore described extends, the slot 60 permitting a movement of the transfer disk 85 back and forth through an arc of substan-

tially 120 degrees. The outer sealing plate 3 is also provided with a curved slot 33 which lies directly above the slot 32 and with an opening 34 which lies directly above the opening 30 in the member 25. The key 14 in one edge is notched as indicated at 70 35 to conform to the projection 31 which extends into the opening 30, the projection guiding the key properly in the opening 30. On one side the key has three curved grooves 75 36, the opposite side being provided with two similar curved grooves 37.

In operation when the plug is inserted in the casing it passes through the recess 23 in the transfer disk 21, thereby holding the 80 disk against movement. When the plug is drawn to the position shown in Fig. 8 the shoulders 18 stop it at a point such that the transfer disk 21 may be turned through the slot 13 in the plug. When the disk is turned 85 so that the handle 24 is in the position indicated in Fig. 1 the recess 23 comes in direct conjunction with openings 30 and 34. A key 14 may now be inserted and is guided by the projection 31 so that the slots 36 thereof receive the ribs 19, the key entering into the recess 23 of the transfer disk. By turning the disk through a partial revolution or until the operating pin 24 is carried to the end of the slot opposite that shown in Fig. 95 1, the key is carried into the slot 13 of the plug 11 and may be transferred with the plug inwardly to perform its function by engaging against the incline 10^a of the arm 10 as heretofore described.

100 From the foregoing it will be apparent that I have provided a novel and useful transfer means for carrying unlocking keys to operative position and one which will insure against the use of any except keys of a particular construction. The guiding ribs 105 19 and 27 and the guiding projection 31 render it imperative that the key shall have a special construction and the transfer mechanism described, including the grooves transfer disk and the associated ribs 19 and 27 entering said grooves, render it impossible to use any other type of key.

110 I claim:—

115 1. In combination, an inclosing casing, a plug having a transverse slot between its ends movably mounted in the casing and adapted to be projected a distance outside the casing with the slot in the plug located within and adjacent a side of the casing, and a transfer means movably mounted within said side of the casing in association with the plug, and adapted to receive a key from without the casing and carry it to the slot in said plug.

120 2. In combination, an inclosing casing, a plug having a transverse slot movably mounted in the casing and capable of projection partially outside the casing, means limiting the outward movement of the plug, a 125 130

- transfer disk rotatably mounted on the casing and having a recess at one side through which the plug passes, thereby holding the disk against rotation except when the plug 5 is moved with its slot lying in the same plane as the disk and means covering the transfer disk having openings leading from without the casing to the disk for the insertion of a key into the recess in the disk, substantially 10 10 as described.
3. In combination, a casing, a cover for one side thereof, a transfer disk rotatably mounted on the cover having a recess at one edge thereof, a plug having a transverse slot 15 movably mounted in the casing passing through the cover and the recess of the disk, means covering the disk, means on said means stopping the outward movement of the plug with the slot thereof in the same 20 plane as the disk, means to manually rotate the transfer disk, and means permitting the insertion of a key in the recess of the transfer disk when rotated away from its normal position, substantially as described.
- 25 4. In combination, an inclosing casing, a plug having a transverse slot therein mounted in the casing and adapted to be projected a distance outside the casing with the slot in the plug located adjacent one side of the 30 casing, a transfer disk rotatably mounted adjacent the plug having a recess through which the plug passes, and means covering the transfer disk, said means having an opening to permit the entrance of a key into 35 the recess in the disk when the plug is projected outwardly to permit the rotation of the disk through the slot thereof.
5. In combination, a casing, a cover for the casing, a transfer disk having a recess 40 at one edge mounted on the cover, a member attached to the cover over the transfer disk, a sealing plate secured over the cover and said member, the member and cover having registering openings leading to the transfer 45 disk, means to turn the transfer disk about its center as an axis, and a plug having a transverse slot mounted in the casing and extending through the cover, sealing plate and member between them and positioned 50 in the recess in the transfer disk.
6. In combination, a casing, a cover for the casing having a depression therein, a transfer disk rotatably mounted in the depression, said disk having a recess at one 55 edge, a member secured to the cover and seating in the depression over the transfer disk, a sealing plate over the cover and said

member, the sealing plate and member having registering openings leading to the transfer disk, means to turn the transfer 60 disk from without the casing, and a plug having a transverse slot mounted in the casing and extending through the cover, sealing plate and the member between them and positioned in the recess in the transfer disk. 65

7. In combination, a casing, a cover for the casing having a substantially circular depression therein, a circular transfer disk in the depression mounted to turn about its center as an axis and having a recess at one 70 edge, a member secured to the cover and seating in the depression above the transfer disk, said member having a circular opening therethrough, a projection extending into the opening, a sealing plate over the cover 75 and member provided with an opening registering with the opening in said member, an operating handle on the transfer disk extending through slots in said member and sealing plate, and a plug having a transverse slot mounted in the casing with an end 80 extending through the cover, sealing plate and the member between them and positioned in the recess in the transfer disk.

8. In combination, a casing, a cover for 85 the casing having a substantially circular depression therein, a circular transfer disk in the depression mounted to turn about its center as an axis and having a recess at one edge and concentric grooves in both sides 90 thereof, a member secured to the cover seating in the depression above the transfer disk having a circular opening therethrough, a projection extending into the opening, concentric ribs on the member seating in 95 grooves on one side of the transfer disk, similar concentric ribs on the cover plate seating in grooves on the other side of the transfer disk, a sealing plate over the cover and member provided with an opening communicating with the opening in the member, an operating handle on the transfer disk extending through slots in the member and sealing plate, and a plug having a transverse slot mounted in the casing with an end 100 105 extending through the cover, sealing plates and the member between them and positioned in the recess of the transfer disk.

In testimony whereof I affix my signature in presence of two witnesses.

WILLIAM E. ELLIOTT.
